UNITED STATES PATENT OFFICE.

MAURITZ W. HOGLUND, OF NEW YORK, N. Y.

DESIGN FOR A CLEAT FOR FIRE-ESCAPES.

SPECIFICATION forming part of Design No. 32,094, dated January 9, 1900.

Application filed December 6, 1899. Serial No. 739,446. Term of patent 7 years.

To all whom it may concern:

Be it known that I, MAURITZ W. HOGLUND, a citizen of the United States, residing at New York, (Brooklyn,) in the county of Kings and State of New York, have invented and produced a certain new and original Design for Cleats for Fire-Escapes, of which the following is a full, clear, and exact description.

The object of this design is to provide a new and original shape or configuration of the metal cleat used in rope fire-escapes.

In the accompanying drawings, illustrating my design, in the several figures of which like parts are similarly designated, Figure 1 is a perspective view. Fig. 2 is a side elevation. Fig. 3 is an elevation viewed from the right-hand side of Fig. 2, and Fig. 4 is an elevation viewed from the left-hand side of Fig. 2.

As shown in the drawings, the leading or material feature of my design consists of the irregularly-disposed openings *a b c* in the casting *d*, having the externally-flattened walls *e f g* and the intervening thin flat webs *h i*, which walls and webs give to the opposite sides of the cleat a series of alternating elevations and depressions. The adjacent open-

ings *a b* have in common the elongated mouth-cavity *j*, and the openings *f g* have in common the elongated mouth-cavity *k* on the side opposite the cavity *j*. The casting *d* is provided at one end with a flattened eyepiece *l*, and at the opposite end and from one side projects the trough-like piece *m*.

Viewed from the left-hand side of Fig. 2, it will be observed that the openings *e* and *f* have an upward slant relatively to the right-hand side and that the opening *g* similarly has a downward slant, the dotted lines in Fig. 2 indicating the relative arrangement or configuration of the several openings *e, f*, and *g*.

Having described my invention, what I claim as new, and desire to secure by Letters Patent, is—

The design for a cleat for a fire-escape, substantially as herein shown and described.

In testimony whereof I have hereunto set my hand this 1st day of December, A. D. 1899.

MAURITZ W. HOGLUND.
